SPARK ARRESTER

Cecil M. Rogers, Chicago, Ill., assignor to Locomotive Firebox Company, Chicago, Ill., a corporation of Delaware

Application September 22, 1933, Serial No. 690,507

7 Claims. (Cl. 230—97)

This invention relates to improvements in spark arresters and it consists of the matters hereinafter described and more particularly pointed out in the appended claims.

5 The spark arresters with which my invention is more particularly concerned include means providing a centrifugal separator chamber. To operate efficiently, said chamber must have an inlet properly proportioned with respect to the 10 flue area opening into the smoke box. However, the space left in the smoke box by reason of the location of the necessary steam pipes, superheater and other parts, is often too small to accommodate a spark arrester having the capacity 15 required for the locomotive.

Under such conditions, the installation of a spark arrester of sufficient capacity, requires certain changes in the associated parts of the locomotive. In some instances, the smoke box 20 must be lengthened forwardly and in other instances, the stack requires moving forwardly. Again, at times it is necessary to provide an exhaust pipe or nozzle having an offset end in lieu of the existing one. These changes entail considerable expense for parts and labor and greatly increase the cost of installation. This it is 25 desired to avoid.

One of the objects of the present invention is to provide a spark arrester of ample capacity, 30 which may be readily installed in a relatively small space, and has its parts so formed and arranged as to provide sufficient capacity as well as an inlet of an area equal to or greater than that of the flues opening into the smoke box.

35 A further object of the invention is to provide an arrester including a casing providing the main separator chamber and parts coating therewith and with the smoke box shell in providing an auxiliary separator chamber that communicates with the main separator chamber, both chambers having a common inlet in which is provided means initiating a whirling of the gases and cinders entering both chambers through said inlet.

45 The above mentioned objects of the invention, as well as others, together with the many advantages thereof, will more fully appear as I proceed with my specification.

In the drawings:

50 Fig. 1 is a longitudinal vertical sectional view through a locomotive front end provided with a spark arrester embodying one form of my invention;

Fig. 2 is a transverse vertical section there- 55 through as taken on the line 2—2 of Fig. 1;

Fig. 3 is a longitudinal horizontal sectional view through the same as taken on the line 3—3 of Fig. 1; and

Fig. 4 is a transverse vertical sectional view through the arrester and associated parts as taken on the line 4—4 of Fig. 3.

In general, my improved arrester includes an upright casing arranged in the smoke box and enclosing portions of the stack and nozzle. Parts are arranged in the smoke box shell to coat 10 therewith and with the casing to provide an auxiliary separator chamber above, but in communication with the main separator chamber as provided by the said casing. A common inlet is provided at the front, for both chambers so that 15 both chambers are influenced by the draft action of the blast up the stack. With such an arrangement, a part of the shell itself in which certain steam pipes and other locomotive parts are located and heretofore not available for other pur- 20 poses, is made to function as a part of the separator chamber of the arrester. Thus an arrester of sufficient capacity is obtained without requiring expensive alterations in the locomotive front 25 end structure to accommodate the same. 25

Referring now in detail to that embodiment of the invention illustrated in the drawings:

1 indicates as a whole the shell of a locomotive boiler, 2 indicates the smoke box shell and 3 indicates the front flue or tube sheet of the boiler 30 in which the front ends of the tubes or flues 4 are secured in the customary manner. The open front of the shell 2 is closed by the usual front end and door 5. In the rear portion of the smoke box is located a header 6 to which superheater 35 tubes 7, arranged in certain of the flues or tubes 4 of the boiler, are operatively connected.

Also located in the smoke box, at each side near the top are the usual elbows 8 which are connected to the superheater header 6 and the 40 curved pipes 10 that follow down about each side of the smoke box shell to lead to the associated cylinders, not shown.

11 indicates the exhaust pipe having a flanged top to which the flanged bottom of the nozzle or 45 tip 12 is secured. 13 indicates the smoke stack arranged axially of the nozzle or tip and secured to the bottom end of said stack is an ex- 50 tension 14 having a flared bottom 15.

16 indicates as a whole an arrester casing ar- 55 ranged in the smoke box to constitute the main separator chamber of the arrester and which is of such a transverse width as to leave a space be- 50 tween each side thereof and the smoke box shell for the passage of the steam pipes 10. This cas-

- ing, which is open at the front and the greater part of its top, includes an upright side wall having an arcuate rear portion 17, an arcuate side portion 18 and a straight side portion 19 so as to leave an inlet opening 20 for the casing at the front thereof. The axis of the casing portions 17 and 18 may be offset forwardly of the plane of the axis of the stack and nozzle respectively.
- 10 21 indicates the flat horizontal bottom wall of the casing which is of a plan contour fitting the upright wall of the casing. This bottom wall has a portion arranged and clamped between the adjacent flanges of the nozzle and tip respectively 15 and rising from said wall, concentric with the tip, is a race ring 22. Following about the top end of the upright wall of the casing is an angle bar stiffener ring 23.

Extending transversely across the smoke box shell, a suitable distance rearwardly of the stack extension 14, is a rear baffle wall 24. This wall follows the top part of the shell 2 and terminates at its bottom end in a plane of the top edge of the arrester casing. Said wall is preferably made 25 in side and central sections 25 and 26 respectively and which sections meet edge to edge in planes radial with respect to pipe portions connecting the elbows 8 with the superheater header as best shown in Fig. 4. In the central section of this 30 wall is a door 27 whereby access may be had to the shell 2 rearwardly of said wall for inspection purposes. A top wall portion 28 is provided for that part of the casing 16 rearwardly of the baffle wall 24 to close off that part of the top of the 35 casing.

In the plane of the open front or inlet of the casing at each side thereof is provided a baffle plate 29 and 30 respectively. Said baffle plates extend upwardly from the bottom of the casing 40 to a point above the plane of the top of the casing as provided by the wall 28 previously mentioned. The top ends of said plates may be connected together by a transverse top baffle plate 31, and all of said plates are fixed to a ring 32 45 on the inside of the shell 2. The baffle plates just mentioned, together with the baffle plate 24 in connection with the intervening part of the shell 2, coact to form an auxiliary separator chamber 33 above, but in communication with that part 50 of the main separator chamber forward of the plate 24.

The baffle plates 29, 30 and 31 coact to form an inlet 34, common to both separator chambers mentioned. With such an arrangement, it is possible to provide an arrester inlet having an area exceeding that of the flue's ends 4 in the flue sheet 3. In said inlet 34 toward the side 18 of the casing are provided laterally spaced deflectors 35 which extend from the top to the bottom of the inlet. These deflectors in connection with another deflector plate 36 arranged between the baffle 29 and end of the casing wall part 18, act to direct the incoming gases and cinders toward the straight wall side 19 of the casing.

65 Along each side of the casing, extending from the front to the rear and arranged substantially in the horizontal plane of the top of the casing, are horizontal wall parts or shelf plates 37 and 38 respectively. In each shelf plate is provided 70 an opening 39 and associated closure for the passage therethrough of the steam pipes 10.

Also associated with each shelf plate 37-38 is an inward extension 40 or 41 respectively, both of which are inclined upwardly toward the stack 75 extension to terminate short thereof. The ex-

tension 40 has a lesser length longitudinally of the smoke box shell than the extension 41 as best shown in Fig. 3 to leave an opening 42 of a somewhat irregular outline by which the auxiliary separator chamber 33 communicates with the main separator chamber as provided by the casing 16.

In the operation of the arrester, the gases and cinders as they enter the smoke box must pass downwardly and under the casing 16 before they 10 can enter the inlet 34 to both chambers. Due to deflector plates 35-36, in connection with the draft action as produced by the nozzle and stack, a whirling action is initiated for the gases and cinders entering the said common inlet. 15

As the products of combustion, sparks, cinders, etc. enter the upper or auxiliary separator chamber of the spark arrester and pass in a sweeping path toward the rear, there might normally be a tendency for them to sweep downwardly into the main separator chamber without passing around the rear side of the stack extension. It will be noted that there is but a relatively narrow throat or space between the rear portion of the stack extension and the wall 24 as best shown in Fig. 3. Thus if the auxiliary and main separator chambers of the spark arrester were in wide open communication vertically, that volume of the products of combustion originally entering the upper auxiliary separator chamber might be 30 quickly deflected and caused to move immediately into the lower main separator chamber of the arrester with the attending danger of passing out of the stack before the sparks could be reduced in size or extinguished. By providing the two 35 members 40 and 41 which substantially divide the spark arrester into upper and lower chambers the products of combustion entering the upper chamber are prevented from taking an immediate sweep downwardly into the main separator chamber. In this way, a sufficient time element is provided for the cooling or extinguishing of the products of combustion before they can possibly be discharged through the stack.

Also some of the heavier particles as they enter 45 the auxiliary chamber and whirl, by chance may impinge against the steam pipe 10 and its elbow above the shelf plates 37-38. Such particles will immediately fall upon the extensions 40 and 41 to sooner or later be caused to move off said 50 plates by draft action and to enter the main separator chamber through the connecting opening 42. Thus such large sparks or cinders are not only given time to cool off to harmless temperature but they are also prevented from immediately dropping into the main separator chamber after impinging upon said pipes and elbows. Thus they cannot be entrained up the stack while in a condition capable of starting 55 wayside fires.

Such gases and cinders as enter the main separator chamber are caused to whirl in a circular path about the inside of the casing so that they are broken up into finer and cooled off particles which are entrained by draft action for 65 passage up the stack for a harmless discharge.

By the construction described it is apparent that space in the smoke box shell heretofore unused for spark arresting purposes, is made to function as an auxiliary separator chamber that 70 is in communication with the main separator chamber so as to form in effect, an enlargement for the main separator chamber.

By making use of smoke box shell space, heretofore unused for separator purposes, I am en- 75

abled to provide an arrester, which requires no expensive alterations of the locomotive parts in the smoke box and at the same time to provide separator chamber space and inlet therefor having a capacity insuring efficient locomotive operation. Again, with the arrangement described, the casing may be of such size as to be easily assembled through the open front of the smoke box and at the same time leave ample space for 10 steam pipes and the like without requiring any change therein.

While in describing the invention, I have referred in detail to the form, arrangement and construction of the various parts thereof, the 15 same is to be considered only in the illustrative sense so that I do not wish to be limited thereto except as may be specifically set forth in the appended claims.

I claim as my invention:

- 20 1. In combination with a locomotive smoke box shell and associated smoke stack and exhaust nozzle, a sheet at the rear end of the smoke box shell and having flues opening therethrough, an arrester casing in said shell and enclosing portions of both the stack and nozzle and providing a main separator chamber, means providing an auxiliary separator chamber in the shell above but in communication with the main separator chamber, and means in communication with said flues and providing an inlet for combustion gases from said flues into both chambers and including parts arranged to initiate a whirling of the said gases and cinders therein entering said chambers therethrough, said inlet having an area substantially greater than that of the flues opening through said sheet.
- 25 2. In combination with a locomotive smoke box shell and associated smoke stack and nozzle flues opening into said shell, an arrester casing in the shell and enclosing portions of both the stack and nozzle and providing a main separator chamber, means providing an auxiliary chamber in the shell above said casing and communicating with the central portion of the main separator chamber by an opening arranged about a part of the smoke stack, and means in communication with said flues and providing an inlet for combustion gases from said flues into both chambers and including parts arranged to initiate a 30 whirling of said gases and the cinders therein entering said chambers therethrough.
- 30 3. In combination with a locomotive smoke box shell and associated smoke stack and nozzle flues opening into said shell, an arrester casing in said shell and enclosing portions of both the stack and nozzle and providing a main separator chamber above the casing, means closing off the bottom of said auxiliary chamber to each side of the stack and so formed as to provide a communication between said chambers adjacent the stack, and means in communication with said flues and providing an inlet for combustion gases from said flues into both chambers and including parts arranged to initiate a whirling of said gases and the cinders therein entering said chambers therethrough.
- 35 4. In combination with a locomotive smoke box shell and associated smoke stack and nozzle, an arrester casing in said shell and enclosing portions of both the stack and nozzle and providing a main separator chamber, means providing an auxiliary chamber above the casing, means arranged between said chambers and terminating short of the smoke stack to provide a commun- 40

5 eating opening between said chambers and surrounding the stack, means providing an inlet for both chambers and arranged to initiate a whirling of the gases and cinders entering said chambers therethrough, and means in said auxiliary chamber against which a portion of the gases and cinders entering said auxiliary chamber engage before passing through said communicating opening so that the cinders are broken up thereby.

10 5. In combination with a locomotive smoke box shell and associated smoke stack and nozzle, an arrester casing in said shell and enclosing portions of both the stack and nozzle and providing a main separator chamber, a baffle plate between the shell and the rear top end part of the casing, a second baffle plate arranged forwardly of the first baffle plate and connected to the top part of said shell and to said casing and terminating short of the bottom of said shell to leave a 15 passageway to that part of the shell forwardly of said second baffle, means extending inwardly from each side of the shell in the plane of the top of the casing to define an auxiliary separator chamber communicating with said main chamber, said second baffle plate having an opening therein providing an inlet for both chambers, and means associated with said opening for initiating a whirling of the gases and cinders entering said chambers through the inlet.

20 6. In combination with a locomotive smoke box shell and associated stack and exhaust nozzle, front and rear baffle members in the top of the smoke box shell, there being an opening in the front baffle member, means providing a horizontal wall having an opening therein through which the stack extends and which wall coacts with said baffle members and associated part of the smoke box shell respectively to define a separator chamber of rectangular shape when viewed from above, a casing having an opening in the front, arranged below said wall and spaced from the sides of the shell and providing a second separator chamber enclosing parts of the stack and nozzle and in communication with the first 25 mentioned chamber by means of said opening in said horizontal wall, said second chamber when viewed from above being substantially cylindrical, said openings in said baffle member and in said casing respectively providing the inlets for said 30 chambers, and means in said inlets for initiating a whirling of the products of combustion as they enter said chambers through said inlets.

35 7. In combination with a locomotive smoke box shell and associated stack and exhaust nozzle, front and rear baffle members in the top of the smoke box shell, means providing a horizontal wall having an opening therein through which the stack extends and which wall coacts with said baffle members and associated part of the smoke box shell respectively to define a separator chamber of rectangular shape when viewed from above, means arranged in each side of said chamber and against which portions of the products of combustion entering said auxiliary chamber engage to be broken up thereby, said casing providing a second chamber enclosing parts of the stack and nozzle and in communication with the first mentioned chamber by means of said opening and which chamber when viewed from above is substantially cylindrical, there being an opening at the front of each chamber providing an inlet therefor, and means in said inlets for initiating a whirling of the products of combustion entering said chambers through said inlets.
